UNITED STATES PATENT OFFICE.

CHARLES BARNES AND FRED MAWER, OF LINCOLN, ENGLAND.

DRAFT-PREVENTER.

SPECIFICATION forming part of Letters Patent No. 712,240, dated October 28, 1902.

Application filed January 31, 1902. Serial No. 92,046. (No model.)

To all whom it may concern:

Be it known that we, CHARLES BARNES and FRED MAWER, subjects of the King of Great Britain, residing at Lincoln, in the county of Lincoln, England, (whose full postal addresses are Hamilton House, St. Catherine's road, Lincoln, and 3 Bank street, Lincoln, respectively,) have invented certain new and useful Improvements in Draft-Preventers, (for which application has been made in Great Britain, No. 23,859, dated November 25, 1901,) of which the following is a specification.

This invention has for its object a simple and cheap draft-excluder for the bottoms, sides, and tops of doors and other like places. It is best described by aid of the accompanying drawings, in which—

Figure 1 is a perspective view of the bottom of a door with our appliance attached thereto in operation; Fig. 2, a view of the device stretched out flat; Figs. 2^a, 3, 4, 5, 6, and 6^a, transverse sections of modifications of our device, showing the door.

Like letters refer to like parts in all the drawings.

In the drawings, A is the strip of any tough flexible material. It can be formed of rubber, woolen cloth, horsehair cloth, felt, leather, or other material of a tough flexible character.

B is a beading of timber or metal cemented to each edge of the strip. This beading of timber or metal can, however, be riveted or tacked or otherwise fixed to each edge of the strip instead. Fig. 2^a shows the metal beading folded with the strip and having holes punched through both, as shown, so as to fasten the flexible material within the folds.

C is a series of nails attaching the strip to the door. We may sell the strips with the holes for these nails bored, so that any person can at once apply the nails, placing them in the holes. In place of nails, screws or other material, such as glue, can be used to fix the strip in place. D is the woodwork of the door, the bottom of which is usually about one-quarter to three-eighths of an inch from the floor. Fig. 3 shows the three of these strips united. This is just to show that any number of strips can be used, so as to make the article a little stiffer. Fig. 4 shows the strip thickened in the center. This thickening can be formed

as shown in the sketch or by a second piece being cemented or solutioned to the main piece, or the material in weaving can be formed thicker in or near the center than at other points. We may also form the wearing part with a thick coating F, of rubber, flexible varnish, or other composition, as set forth in Fig. 6, permeating or firmly fixed by solution to the cloth. Where rubber or leather is used, we may varnish it on the outside with any smooth slipper varnish, so as to enable the material to slide easily over the floor. In some instances, as in Fig. 5, we may fill the hollow space E with down, sand, or other material, so as to cause the cloth to normally press against the ground, each end of the space E being suitably closed when the strip is fixed. In Fig. 6^a we have shown the same structure as in Fig. 6, with the hollow space E filled with the same class of material as in Fig. 5. We have described it only for the bottoms of doors; but it is obvious that by simply placing the drawing on one side it is shown for the side of doors or by turning it upside down it shows the invention as applied to the top of a door.

We declare that what we claim is—

1. As a new article of manufacture a draft-excluder consisting of two bars B, a flexible strip between them of greater width than the distance between them when in normal position, and a smooth elastic composition firmly adhering to the flexible material at its wearing part whereby there is less friction on the floor or jambs of the door and less wear on the material.

2. As a new article of manufacture, a draft-excluder comprising a strip of material flexible near each edge and thickened for a space intermediate its edges, and two bars secured at the edges of the strips, said bars being arranged for attachment to the edges of a door with the portion of the flexible edges and all of the intermediate thickened portion projecting beyond the edges of the door, with the flexible edges in place to permit of the bending laterally of the projecting portion, and the thickened portion bearing against the frame and taking all of the wear.

3. A draft-excluder comprising a flexible strip of material of a width greater than the

thickness of the door to which it is attached, bars secured to each edge of the strip and attached to the edges of the door with the strip projecting in the form of a laterally-flexible loop beyond the edges of the door, and a stuffing material filling the hollow space between the loop and the edge of the door.

5 In witness whereof we have hereunto signed

our names, this 17th day of January, 1902, in the presence of two subscribing witnesses. 10

CHARLES BARNES.
FRED MAWER.
